US0D1087163S

(12) **United States Design Patent** (10) **Patent No.:** **US D1,087,163 S**
(45) **Date of Patent:** **** Aug. 5, 2025**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Eunsil Lim**, Suwon-si (KR); **Minho Yang**, Suwon-si (KR); **Yeonjoo Jwa**, Suwon-si (KR)

(73) Assignee: **SAMSUNG ELECTRONICS CO., LTD.**, Suwon-si (KR)

(**) Term: **15 Years**

(21) Appl. No.: **29/883,869**

(22) Filed: **Feb. 3, 2023**

(30) **Foreign Application Priority Data**

Aug. 4, 2022 (KR) 30-2022-0031587

(51) **LOC (15) Cl.** **14-04**

(52) **U.S. Cl.**

USPC **D14/485**

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outer perimeter shown as dashed broken lines in the figures illustrates a display screen or portion thereof and forms no part of the claimed design. The remaining dashed broken lines in the figures illustrate portions of the graphical user interface that form no part of the claimed design.

1 Claim, 2 Drawing Sheets
